UNITED STATES PATENT OFFICE.

ANDY F. PARKER, OF ROYSE CITY, TEXAS.

CULTIVATOR ATTACHMENT.

1,187,859.

Specification of Letters Patent. Patented June 20, 1916.

Application filed September 18, 1915. Serial No. 51,468.

To all whom it may concern:

Be it known that I, ANDY F. PARKER, a citizen of the United States, residing at Royse City, in the county of Rockwall and State of Texas, have invented certain new and useful Improvements in Cultivator Attachments; and I do hereby declare the following to be a full, clear, and exact description of the invention, such as will enable others skilled in the art to which it appertains to make and use the same.

This invention relates to cultivators, and the primary object of the invention is to provide means whereby the angle of the cultivating shovels may be altered, for regulating the depth of insertion into the ground, without necessitating the operator's alighting from the seat of the cultivator, and unloosening various bolts and readjusting the shovel-carrying standard.

Another object of this invention is to provide a cultivator attachment as specified which is adapted for attachment to any ordinary type of wheeled straddle row cultivator, which includes a lever and dog mechanism associated therewith, which co-acts with a notched member, for holding the shovel-carrying standard in various positions for regulating the depth of insertion of the cultivating shovel, and also by means of which the angle of the shovel may be varied by pivotal movement of the lever.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views, and in which:

Figure 1 is a fragmentary side elevation of a cultivator, showing the improved invention attached thereto, Fig. 2 is a fragmentary plan view, Fig. 3 is a fragmentary side elevation of the improved cultivator attachment, Fig. 4 is a central section through the attachment, Fig. 5 is a detail perspective view of a part of the attachment.

Referring more particularly to the drawings, 1 designates the cultivator standard supporting beam, of any suitable type of wheeled straddle row cultivator, which has secured thereto, at spaced intervals along its

length, blocks 2. The blocks 2 preferably have their lower surfaces curved, as is shown at 3, and their upper surfaces flat, for resting against the under surface of the beam 1. 60 The blocks 2 project to one side of the beam 1, and are hollow, having sleeves 5 mounted centrally therein. The sleeves 5 have bolts 6 extending longitudinally therethrough, and through plugs 7, which are mounted in 65 the ends of the blocks 2, as is clearly shown in Fig. 4 of the drawings. The bolts 6 have eyes 8 formed in their ends remote from the end which extends through the plugs 7. The standards 9, which support the cultivator shovels 10, extend through the eyes 8 of the eye-bolts 6, and rest in the substantially semi-circular shaped sockets 11 formed in the pillow blocks 12. The pillow blocks 12 are secured to the outer surface of a disk 13, 75 which is mounted upon the sleeve 5. Each of the disks 13 is provided with a radially extending recess 14, into which the inner end of a hand lever 15 extends. The hand lever 15 has a dog mechanism 16 of the ordinary construction, secured thereto, which is automatically held in a locking position, by means of the spiral spring 17. The catch or last end of the dog mechanism 16 is provided for engagement with notches 18, 80 which are formed about the portion of the circular surface of a member 19. The member 19 is also mounted upon the sleeve 5, inwardly of the disk 14, and toward the standard 1. The member 19 has an upstanding 85 arm 20 formed thereupon, which is provided with a notch 21. The notch 21 extends inwardly from one surface of the elongated arm or head 20, which is formed upon the member 19, and is provided for receiving a 90 bolt or the like, which is indicated at 22, and extends through a notch 23, formed in the member 24. The member 24 is mounted upon the sleeve 5 inwardly of the member 19, and is preferably secured to the end of the 95 block 2. The member 24 is shaped like the member 19, and is identical therewith, in all respects, with the exception of the notches 18, which are formed in the member 19. The notches 18 are preferably formed in 100 one corner of the member 19, as is clearly shown in Fig. 5 of the drawings.

When starting to cultivate grain, the standards 9 may be adjusted to any desired angle for regulating the depth of insertion 110 of the shovels 10 into the ground, and during the cultivating operation, if conditions

should necessitate the changing of the depth of the shovels, this operation may be easily accomplished, by releasing the dog mechanism 16, and moving the lever 15, for rotating the member 19 and the disk 13, any desired distance within the scope of the leverage action of the lever 15, for varying the angle of the standards 9 with respect to the beam 1, which will regulate the position 10 of the shovels 10, as desired. By the improved construction heretofore described, and illustrated in the drawings, this work, of changing the elevation of the shovels, may be performed without necessitating the 15 removing of any bolts, pins or the like, and also without the operator's alighting from the seat of the cultivator, when the construction is used upon a riding cultivator.

While it has been referred to in the specification, as a riding cultivator, it is to be understood that the invention may be applied to any desired type of walking or riding cultivators, without departing from the spirit of this invention.

25 In reducing the invention to practice, certain minor features of construction, combination, and arrangement of parts may necessitate alteration, to which the patentee is entitled, provided such alterations are 30 prehended within the scope of what is claimed.

What is claimed is:—

1. In an attachment for wheeled straddle row cultivators, the combination, with a cultivator standard supporting beam, of blocks 35 secured to the beam, sleeves rotatably

mounted with said blocks, disks mounted upon the ends of said sleeves, eye-bolts extending longitudinally through said sleeves, cultivator standards connected to said eye-bolts and held in engagement with the outer surfaces of said disks by said bolts, and means operatively connected to said disks for rotating the disks for changing the angle of said cultivating shovel carrying standards. 40 45

2. In an attachment for wheeled straddle row cultivators, the combination, with a cultivating shovel standard carrying beam, of a plurality of blocks secured to said beam, 50 sleeves rotatably mounted centrally within said blocks, disks mounted upon said sleeves, cultivating shovel carrying standards, eye-bolts connected to said standards and extending longitudinally through said sleeves for holding said standards tightly against said disks for movement with the disks, a member mounted upon said sleeves and abutting said disks, said member having a plurality of notches formed therein, a 55 lever carried by said disks, a dog mechanism carried by said lever for co-action with said notches, said lever adapted for rotating said disks for changing the angle of said standards. 60 65

In testimony whereof I affix my signature in presence of two witnesses.

ANDY F. PARKER.
